3,188,938 VENTILATING DEVICE

Edward C. Hallock, 36 Woodland Ave., Summit, N.J.
Filed June 12, 1963, Ser. No. 287,252
6 Claims. (Cl. 98—121)

This invention relates to ventilating devices and, more particularly, to an improved method of fabricating ventilating devices of the type suitable for installation in masonry or concrete walls, and to an improved ventilating device.

In the construction of interior partitions and exterior walls in closed spaces in buildings such as basements, crawl spaces, attics, and the like, a number of types of small ventilating devices have been employed to prevent moisture from accumulating and for cooling or air circulation intake. Known forms of ventilating devices, for example, simple grille plates, box-like ventilators having perforated front surfaces, or somewhat more elaborate cast ventilators, have been fabricated from sheet metal or have been made by casting. As so constructed, sheet metal ventilators require the provision of a suitable opening in the wall with a lintel used to support the wall above the opening. The ventilator or grille plate is then installed in the opening. Presently known cast ventilators, while having the advantage of being of sufficient strength to support the wall structure above the ventilator, have substantial limitations inherent in casting methods. For example, casting restricts the size and geometry of the ventilator and limits the amount of free area for the openings. Also, cast metals are generally weak and brittle, making them subject to cracking, contain structural defects occurring during manufacture, and are relatively poorly adapted to receive finishes, such as anodizing or baked enamel.

These and other disadvantages and limitations of known forms of ventilating devices are overcome in accordance with the invention by a novel and improved method of fabricating a modular ventilating device of the type suitable for direct installation in masonry or concrete walls. More particularly, a ventilating device is produced by the extrusion of a channel-shaped member of predetermined configuration, forming apertures in the front side or web of the channel member, and selectively mounting transverse support plates between its top and bottom flanges. The support plates may also be extruded and have bosses formed on one or on both sides for receiving fasteners from the flanges of the channel member and for contributing to the structural rigidity of the ventilator. In order to simplify fabrication of a wide variety of different sized ventilators and substantially reduce the cost of production, the channel member and the support plates may be continuously extruded, in accordance with well known extrusion techniques, and then may be selectively cut off at the appropriate lengths. Suitable louvered apertures may be formed in the web of the extruded channel member, for example, by slitting the web and pressing the slit portions into the space between the flanges. The support plates are then placed in position between the flanges and attached thereto.

It is often desirable to install a screen in the ventilating device to prevent the entry of insects, small animals and the like into the building, and advantageously, the screen may be installed, in accordance with the invention, behind the web of the channel member adjacent the apertures and held in place by the bosses on the support plates, thereby eliminating the necessity of other fastening means to retain the screen. Further, in order to prevent moisture from seeping through the joints between the channel member and the support plates, a coating of a suitable sealing compound may be applied at the joints.

2

The method of the invention is readily adaptable to the use of materials such as bronze or aluminum, which have the desirable characteristics of light weight, corrosion resistance, attractive finish, and high strength.

5 The sturdy construction of the ventilating device of the invention renders it useful as an integral structural portion of a wall, thereby affording a substantial reduction in the cost of installation inasmuch as it is unnecessary to construct a reinforced opening in the wall, as is normally required with the present types. Installation is particularly efficient in brick or concrete block walls, since the ventilating device may be of modular size and merely set in place in a course of brick or block, and the adjacent bricks or blocks laid around it. For installation in concrete walls, the ventilating device may be built into the wall forms and concrete poured around it. A ventilating device, in accordance with the invention, is preferably formed with ribs extending longitudinally along the outer faces of the flanges of the channel members to secure the 10 ventilating device in a masonry joint or in concrete. Also, the transverse location of the ribs on the upper and lower flanges, respectively, may be arranged to provide interlocking between two or more vertically stacked ventilating devices.

15 20 25

The use of extruded members together with only a minimum of assembly steps enables considerable savings in the cost of production. An important advantage of the method is that the ventilating devices may readily be formed in any desired length, advantageously, in multiples 30 of the length of a brick or a block, by cutting the continuous extrusion to the desired length and installing transverse plates at appropriate intervals. Extrusion enables the fabrication of ventilating devices having superior strength properties, better appearance, greater adaptability 35 to finishes and more free ventilating area than presently known types.

For a more complete understanding of the invention, reference may be had to the following detailed description, taken in conjunction with the accompanying figures 40 of the drawing, in which:

FIGURE 1 is a front elevational view of a portion of an exemplary embodiment of a ventilating device installed in a wall, in accordance with the invention;

FIG. 2 is a top view of the ventilating device of FIG. 1 with a portion of the upper flange of the channel member cut away in a sectional view taken along the line 2—2 of FIG. 3 and looking in the direction of the arrows;

FIG. 3 is an end view in section taken along the line 3—3 of FIG. 2 and looking in the direction of the arrows;

FIG. 4 is a partial view in vertical section showing an interlocking arrangement between stacked ventilating devices afforded by the transverse location of longitudinal ribs on the flanges of the channel member;

FIG. 5 is an end view in section similar to FIG. 3 of the ventilating device illustrating a clip for holding a screen in place; and

FIG. 6 is a partial plan view in section illustrating the clip of FIG. 5, taken generally along the line 6—6 of FIG. 5.

60 The ventilating device 10, installed in a wall 12, includes a channel member 14, having a web 18 and flanges 22 and 24, extruded from a suitable material, such as aluminum, in accordance with well known techniques. The channel member 14 is severed or cut to an appropriate length from a continuous extrusion, either before or after forming the apertures 15 and the louvered slats 16.

A plurality of elongated apertures 15 are formed in the web 18 of the channel member 14, for example, by cutting or slitting the web 18 to form elongated louvered slats 16 which are pushed back into the space between the flanges 22 and 24 at a suitable angle to the plane of

the web 18. The apertures 15 are more readily and neatly formed in the web 18 if their ends are cut so as to converge slightly in an upward direction at an angle of about 8 to 10 degrees, as illustrated in FIG. 1.

Transverse plates 26 are selectively installed between the flanges 22 and 24 and adjacent the ends of the channel member 14, for example, by one or more screws 28 inserted through suitable openings in the flanges 22 and 24 and engaged by hook-like bosses 30, preferably formed integrally with the plates 26. The bosses 30 eliminate the necessity of providing clips or other fastening means, or of welding to secure the transverse plates 26 in the channel member 14. Advantageously, the plates 26 may also be extruded from the same material as the channel member 14. In addition to serving as convenient receiving means for the screws 28, the bosses 30 also increase the flexural rigidity of the plates 26, thus adding strength to the ventilating device 10 and eliminating the need for special support means such as lintels in the wall in which the ventilating device 10 is to be used.

As aforementioned, the ventilating device 10 may be made in any desired length. When necessary, intermediate transverse support plates 27 may be installed at appropriate intervals along the channel member 14 intermediate the ends, the spacing depending on the strength requirements for the ventilating device. Advantageously, the intermediate plates 27 may have bosses 30 and 30' extruded on both sides, thereby adding greatly to their strength and also affording a retaining means to hold a screen 42 in place, as described in more detail hereinafter.

The ventilating device 10 may have a number of sets of apertures 15 and slats 16 formed therein, and spaced from each other by a solid transverse portion 19 of the web 18, thereby enabling the intermediate plates 27, which extend laterally across the flanges 22 and 24, to bear against the inside of the web 18 of the channel member 14.

In accordance with the invention, the channel member 14 may be formed with longitudinal ribs 32 extending along the outer surfaces of the flanges 22 and 24 to secure the ventilating device 10 firmly in mortar joints 33 in a masonry wall or in a concrete wall. Additionally, the ribs 32 strengthen the flanges 22 and 24. Additionally, as shown in FIG. 4, the transverse locations of the ribs 32 on the upper and lower flanges 22 and 24 may, respectively, be arranged for interlocking two or more vertically stacked ventilating devices, thus eliminating the need for fasteners between them.

The extruded channel member 14 may also include an upper drip molding 34 to prevent water running down the wall of the building from entering the ventilating device 10 and a lower drip molding 36 to prevent leakage at the joint between the lower flange 24 and the wall 12. The upper and lower faces of the upper and lower drip moldings 34 and 36, respectively, may be mated, so as to afford further interlocking between the devices 10, and also to present a neater appearance when stacked, as illustrated in FIG. 4.

In the event that water does enter the ventilating device 10, an upstanding flange 38 extending along the back edge of the lower flange 24 of the channel member 14 will serve as a dam to prevent water from draining from the ventilating device 10 into the building, and water trapped by the flange 38 may be drained out through one or more drain ports 40 located at the bottom of the web 18. The drain ports 40 may be stamped into the web during the forming of the apertures 15.

Birds, insects, or other creatures may be prevented from entering the building through the ventilating device by installing a screen 42 across the back edges of the slats 16. The screen may be box-like with its sides bearing against the interior walls of the ventilator and can be held in place by the bosses 30 and 30' thus eliminating the need for fasteners and simplifying the assembly of the ventilating device 10.

FIGS. 5 and 6 illustrate a clip 44 for retaining screens

in place in units in which the transverse plates 26 are spaced rather far apart and the bosses 30 do not secure the screen in the device as completely as desired. The clip 44 is fabricated from a strip by bending the ends to form a U-shape. The clip 44 is installed in the device so that its base 46 bears against the screen and the ends of the legs 48 and 50 are engaged, respectively, by the downstanding flange at the end of the upper flange 22 of the channel member 14 and by the upstanding flange 33 at the end of the lower flange 24.

Thus there is provided, in accordance with the invention, a method of making ventilating devices which involves the assembly of only two basic extruded parts, the channel member and the transverse plates. Further, the absence of any intricate assembly procedures, such as welding, attaching clips, screws, bolts or the like reduces the time and labor involved and, consequently, the expense of manufacture. A ventilating device, made by the method of the invention, includes a number of features not heretofore feasible in ventilators made by presently known methods. The method also enables the fabrication of a wide variety of ventilating devices of substantial length capable of being readily installed as an integral structural portion of a wall and having the advantages of greater free ventilating area, improved appearance and adaptability to better finishes.

It will be understood by those skilled in the art that the above-described method and embodiment of a ventilating device are meant to be merely exemplary and are susceptible of variation and modification without departing from the spirit and scope of the invention. Therefore, the invention is not deemed to be limited except as defined in the appended claims.

I claim:

1. The method of fabricating a ventilating device, comprising the steps of extruding an elongated channel member of predetermined length having a web, an upper flange extending laterally from one edge of said web at a substantially right angle thereto, a lower flange extending from the opposite edge of said web and lying substantially parallel to said upper flange, said upper and lower flanges extending longitudinally with said web, a short upstanding flange extending along and perpendicular to the edge of said lower flange opposite the edge where said lower flange joins said web, projecting drip moldings extending longitudinally along and outwardly from the corners of said channel member formed by the joiners of said web and said flanges, and a plurality of ribs extending longitudinally along the outer surfaces of said upper and lower flanges; forming a plurality of elongated slats in said web of said channel member; pressing said slats into the space between said upper and lower flanges and at an angle and in louvered relation to said web; forming at least one drain port in said web adjacent said lower flange; extruding a member having at least one longitudinal hook-like boss projecting from one side thereof; severing said extruded member in predetermined lengths to form a plurality of transverse plates; inserting a respective one of said transverse plates into the space between said upper and lower flanges and adjacent each end of said channel member and in contact with said upper and lower flanges and said web to form the end walls of said ventilating device; and securing said transverse plates to said channel member by inserting fasteners through said upper and lower flanges into said longitudinal hook-like bosses.

2. The method of fabricating a ventilating device, comprising the steps of extruding a continuous elongated channel having a web, an upper flange extending laterally from one edge of said web at an angle thereto, and a lower flange extending from the other edge of said web and lying in substantially parallel relation to said upper flange; severing said channel at a predetermined length to form a channel member; forming a plurality of elongated slats in said web of said channel member; pressing

said slats into the space between said upper and lower flanges and at an angle and in louvered relation to said web; extruding a member having at least one longitudinal boss projecting from one side thereof, the boss defining a longitudinal slot for receiving fasteners; severing said extruded member in predetermined lengths to form a plurality of transverse plates; inserting a respective one of said transverse plates into the space between said upper and lower flanges and adjacent each end of said channel member and in contact with said upper and lower flanges and said web to form the end walls of said ventilating device; and inserting fasteners through said upper and lower flanges of said channel member into said bosses to secure said transverse plates to said channel member.

3. A ventilating device, comprising an elongated extruded channel member having a web, an upper flange extending laterally from one edge of said web at an angle thereto, a lower flange extending from the other edge of said web and lying generally parallel to said upper flange, said upper and lower flanges extending longitudinally with said web, a plurality of spaced-apart longitudinally extending elongated apertures formed in the web and longitudinally extending slat means for each of the elongated apertures formed integrally with said web and connected along one side thereof and extending inwardly relative to said channel member at an angle to the plane of said web; a transverse plate mounted adjacent each end of said channel member, each of said transverse plates having a boss extending along the inner surface thereof and aligned generally perpendicular to the flanges, said bosses defining slots for receiving fasteners; and fastener means inserted through said upper and lower flanges of said channel member and into said boss slots for fastening said transverse plates to said channel member.

4. A ventilating device as claimed in claim 3, in which said upper and lower flanges have a plurality of longitudinally extending ribs on the outer surfaces thereof to facilitate mounting said ventilating device in a wall. 40

5. A ventilating device as claimed in claim 4, in which at least two of said ribs are transversely positioned on said upper and lower flanges so as to provide interlocking contact along their edges when the devices are vertically stacked.
6. A ventilating device, comprising an elongated extruded channel member having a web, an upper flange extending laterally from one edge of said web at a substantially right angle thereto, and a lower flange extending from the opposite edge of said web and lying substantially parallel to said upper flange, said upper and lower flanges extending longitudinally with said web, said web having a plurality of spaced-apart longitudinally extending elongated apertures formed therein, at least one drain port in said web adjacent said lower flange, a short upstanding flange extending along and at an angle to the edge of said lower flange opposite the edge where said lower flange joins said web, projecting drip moldings extending longitudinally along and outwardly from the corners of said channel member formed by the joinder of said web and said flanges, and a plurality of ribs extending longitudinally along the outer surfaces of said upper and lower flanges; and a plurality of transverse plates respectively mounted in and adjacent the respective ends of said channel member and forming therewith the end walls of the ventilating device.
